EDUCATIONAL GAME APPARATUS

Norman R. Sterne, New York, N. Y., assignor to
 Autobridge, Inc., New York, N. Y., a corpora-
 tion of New York

Application April 21, 1938, Serial No. 203,399

9 Claims. (Cl. 35—8)

This invention is directed to a game apparatus particularly designed for the playing of bridge whist wherein a player has the option of selecting a particular card from his own hand and a particular card from the exposed dummy hand for proposed play in a particular round or trick and then determine, by instrumentalities forming part of the game, whether the card he has selected is the proper card for play in the particular instance and is the same card that would be played by one expertly proficient in the game.

The primary object of the present invention is the provision of a game apparatus in which the player may have the option of selecting a card according to his own judgment, then determining whether that card is the proper card to be played according to expert determination, and then playing the card determined by the expert to be the proper card, with a view thereby of permitting the player to determine by study or other information why the card selected by him to be played, when proving not to be the card determined by the expert as the proper card, is the improper play and the reason why the expert selects the particular indicated card in order that the player may, through this expert aid in comparison with the original card selection of the player without the expert aid, thus permitting the game apparatus to be primarily of an instructive character to afford the expert knowledge and playing of the game to be at the command of the player for comparison with his own choice of cards, with the result that the improved apparatus permits the playing of the game under continued expert instruction.

The essential object of the present invention is to simplify and improve the detailed construction of game apparatus of this character, previously known and in use, with a view to reducing the cost of the game apparatus as a whole to insure its wider and more universal use and avoid structural disadvantages heretofore present in previously suggested game apparatus of this type.

The game apparatus is also designed for use in connection with the new five-suit bridge game which is a recent development. This game involves the use of five suits of thirteen cards each, four of the suits being the conventional clubs, diamonds, hearts and spades and the fifth suit being marked by a crown or the representation of a crown and referred to as "royals" or "greens," the insignia being usually colored green. In the playing of this game, the cards are presumed to be dealt to the players in the usual manner,

each player receiving sixteen cards and the remaining card being exposed on the board and generally referred to as the "kitty." The bids are made in the usual manner except, of course, the inclusion of the new suit in which bidding may be had, each player considering the "kitty" as a possible card in his hand during the bidding and the successful bidder having the option of discarding a card from his hand or dummy's hand to be substituted by the "kitty" which then becomes a part of the hand from which the discard is withdrawn, such discard being placed face upward on the board.

The improved game apparatus is designed with a view to playing the new game, there being provision for exposing the necessary playing cards, sixteen in each hand, a space on the board for the exposure of the "kitty" and a space on the board for the exposure of the discarded card from the successful bidder or his partner playing as dummy. As the sheet co-operating with the cards contains the representations of the cards which are in fixed relation to each other on the particular sheet, the card exposure slots of the successful bidder and his partner, usually in this game apparatus the South hand as the successful bidder and the North hand as his partner or dummy, each of these hands must include the "kitty" and therefore must have seventeen card exposure slots and the game board must also provide a slot through which the "kitty" is continuously exposed and a further slot through which the discard from either the South or North hand, in the case referred to, may be later exposed. The sheets to be associated with the game board of course include representations of the bids, the sixteen cards for each hand, the "kitty" or seventeenth card in the hand of the successful bidder and his partner, and the slides and numeral indications for indicating the expert plays of the particular hands.

The invention is illustrated in the accompanying drawings, in which:

Figure 1 is a plan view of the game apparatus, the removable indicia sheet being shown in position for use. 45

Figure 2 is a sectional view on the line 2—2 of Figure 1. 50

Figure 3 is an enlarged detail section on the line 3—3 of Figure 1.

Figure 4 is an enlarged detail section on the line 4—4 of Figure 1.

Figure 5 is a plan view of the game apparatus 55

showing the board adapted for the playing of a newly developed bridge game.

The improved game apparatus in the particular form illustrated includes a base 1 formed with a depression 2 of a size to accurately receive the printed playing sheet, the base having a narrow edge margin 4 on three sides. A playing board 5 is appropriately hinged or movably connected to the base preferably through a hinge strip 6 secured to the board and to the base at the edge of the board free of the margin 4.

Indicia sheets 7, preferably of a size to fit more or less accurately in the depression 2 of the base, are provided. These sheets are printed to indicate on two sets of opposed parallel relations, playing card indicia at 8, and inwardly of and in spaced relation with each line of playing card indicia, the sheet is printed to provide bidding indicia 9. The sheet is further printed at 10 with a notation to indicate which hand of the playing card indicia 8 is the dealer and may also contain adjacent this dealer indicia a notation as to whether or not either or both sets of players are vulnerable.

In accordance with the printed matter on the sheet, it will be understood from the description and from the illustration that the sheet is printed to present four whist hands in the playing card indicia, popularly referred to as North, South, arranged as partner hands, and East, West arranged as partner hands. The bidding indicia are printed in accordance with bids determined by the expert for the particular hand with which those bidding indicia are associated.

While the matters referred to are the essential features of the printed sheet, aside from the play indication to be later referred to, it will, of course, be appreciated that the sheet may and preferably does contain information by the expert as to comment on the bidding and as to comment on the plays selected by the expert in the manner to be later defined.

Each printed sheet is preferably printed on opposite sides with, of course, different card layouts and different corresponding bidding indicia for each card layout, and the invention contemplates the provision of any number of such sheets, each different from the others, and readily insertible in the recess below the playing board, thus giving to the user the privilege of playing an unlimited number of different hands by change or reversal of the sheets to enable his construction in the playing of the game to comprehend practically any playing condition which may be met in the playing of the game.

A highly important and essential indication of the printed sheet is the means by which the user gains a knowledge of the proper card to play in successive trick sequences as such play is determined by the expert player according to the layout of the card indicia of the respective hands which are being played. These play indicating indicia consist of distinctive characters, preferably numbers, which are individually aligned in spaced relation with each playing card indicia of each hand.

These play determining characters are indicated at 11 and determine by their sequence the sequence of play of the cards indicated in the playing card indicia 8, such sequences or card playing order being, of course, that resultant from the knowledge of the expert and indicating the order in which the expert play will determine the sequence of the cards in the successive tricks.

The playing board is, of course, to be folded

down over the exposed printed surface of the underlying sheet and this board is formed to enable the player to render visible at will the playing card indicia, the play determining characters for each such indicium, and the bidding 5 indicia. To this end, the playing board is formed with narrow elongated slots 12 having a width and a length to expose through each slot one particular card representation of the playing card indicia and the play determining character which 10 determines the sequence of play of that card.

Thus, the slots 12, if otherwise free, each clearly displays the representation of a single card of the playing card indicia and a single character, in the instance shown a numeral, of the play 15 determining characters. Similar slots 13 are arranged to expose the successive predetermined bids for each hand and a further slot 14 is provided in the board to uninterruptedly expose 20 which hand is dealing and as to whether either or both sets of partners are vulnerable, that is, the data indicated at 10.

The particular game apparatus here described is designed not only for playing the game but for 25 playing the game according to the expert determination of that play while at the same time leaving within the option of the player the privilege of first selecting a particular play according to his own judgment and thereafter gaining a knowledge of what the expert would play in the 30 particular instance in order either to confirm the player's original judgment or to indicate the error of that judgment.

In every instance in the playing of the game, 35 the card actually played in a particular trick is indicated by the expert to be played and the advantage of permitting the player an option of indicating first his own judgment as to a play and then confirming or showing the error of that judgment by gaining a knowledge of what particular card the expert would have played, enables the player to study the expert indication of play as compared with his own judgment and thus improve his knowledge of the game. To this end, the apparatus is a purely educational device in 40 the instruction of the game and while affording the player the initial exercise of his own judgment, the actual play is carried out according to the expert determination and the game thus actually played through the full thirteen tricks. In 45 this particular the apparatus is a game apparatus for the actual playing of the game of bridge whist but with that playing determined by the expert.

The ordinary playing of the game, and in order to permit the player the option of exercising his 50 own judgment as to play in a particular instance and thereafter confirm or show the error of that judgment by determining what the expert would have played, requires that the card indicia of the player, who is of course the declarer, and the card 55 indicia of his partner, who has the dummy hand, be exposed, and to permit the playing option of the player in each of such hands prior to a knowledge of what the expert would have played, it is necessary that the play indicating characters 60 indicating the expert play must be concealed when the card playing indicia are exposed.

To secure this result, a slide shutter 15 is provided for each slot 12. Each of these shutters is preferably though not necessarily metallic and includes a plate 16, the depending side edges of which are formed to provide guides 17 which interfit with and slidably embrace the side edges of the slot. The plate 16 which overlies the slot is provided with an upstanding 75

projection 13 serving to provide a finger-piece through which the shutter may be conveniently moved.

As previously stated, the sheet bearing indicia arranges each card indication and the expert sequence of the playing of that card in alignment so as to be exposed through a particular slot 12. The plate 16 of the shutter is of such length that when moved to one end of the slot, it will cover the card playing indicia ordinarily visible through that slot and expose the card playing indication for that card as determined by the expert. When the shutter is moved to the opposite end of the slot, the card indicia are exposed and the play indicated by the expert concealed. The plate of the shutter is thus comparatively short, the sole requirement being that it be impossible to move this shutter to a position where both the card playing indicia and the expert play indicating character may be simultaneously exposed. One or the other but not both of the card and character must be concealed in any one position of the shutter.

Each slot 13 through which the bidding indications of the sheet are completely exposed, is also provided with a slide 19, the marginal edges of which cooperate with the marginal edges of the slot, as in the shutter 15. As this slide, however, must cover all the bids other than the particular one exposed, the slide includes a formation 20 at one end corresponding in all respects to that of the shutter 15 and a plate extension 21 forming part of the shutter formed end 20 which serves to conceal all bid indications other than the one exposed by the movement of the slide 19 in one direction.

The board may be provided with a series of numerals 22 and a cooperating pointer 23 by which a record may be kept of the tricks gained by each side during the play of one game.

An essential and important characteristic of the present construction is the provision of single open slots through each of which a single card indication and the expert play indicating character are exposed, together with a shutter slidably cooperating with the edges of the slot, of comparatively short length and so arranged as to conceal in any one position of the shutter a knowledge of either the card indicia or play indicating indicia.

The printed sheets are arranged so that one player, say, the South player, is always the declarer. This, of course, is merely for convenience as other dispositions may be made with appropriate changes. As South is the declarer, the shutters 15 controlling the indicia of the respective slots 12 are each moved to a position to expose the playing card indicia of the slots. In other words, South's hand is exposed. The shutters of all other hands are moved to a position to conceal the playing cards of the hands, exposing under these conditions the card playing indicia as determined by the expert. The slides 19 covering the bidding indicia are all moved to a position to conceal such indicia.

South then inspects his exposed playing card indicia and decides upon his bid. Having optionally determined his bid, he then moves the slide 19 covering his bidding indicia to expose the first bid. If he finds that his selection as to bid is correct, the bid stands. If he finds that the expert, as indicated by the bid exposed, has determined upon another bid, the player will endeavor by a further inspection of his cards to determine why his chosen bid was incorrect and

why the expert bid was correct. In this connection, he may, if the sheets contain the desired matter, consult the directions on the printed sheet as to comment on the bids which will aid him in determining why he was in error and show the playing judgment of the expert in determining the expert bid as exposed by the movement of the slide 19. In any event, the exposed bid of the expert is the bid of the hand.

The next player is then supposed to bid his hand. As he is an opponent of the declarer, his card playing indicia remain concealed so the bid of his hand is determined by moving the slide 19 to disclose the expert bid of his hand. The next player, who is the partner of the declarer, makes his bid by the movement of the slide to expose the expert bid, and so with the fourth player. The bidding, if necessary, continues in exactly the manner previously described until, in the instance indicated, the South hand wins the bid and is the declarer. West then leads. As West's playing card indicia are concealed and the expert determined playing indicia exposed, the card lead by West will be that indicated as the first play by the expert play indicating indicia.

For convenience, the expert card playing indicia of the opponents of the declarer are arranged in successive sequence so that the cards may be played successively from one end to the other. If the play indicating indicia characters 11 are numerals, as in the instance shown, the lead of West is that playing card indicia indicated by the exposed numeral 1. To perfect this lead operation, West moves the slide 15 in the slot containing the play indicating numeral 1 to expose the card and cover the numeral. Following this lead of West, all the slides 15 of the playing hand of North are moved to expose the playing card indicia of that hand and conceal the play indicating characters or numerals.

Of course, South, the declarer, plays North's exposed hand as well as his own and as the playing card indicia of North's hand are exposed, South has the option of selecting which card of that hand he will play in response to the known lead of West. Having determined from his own judgment as to which card should be played, he moves the slide cooperating with the slot in which that card is exposed to cover the selected card and expose the play indicating indicia of the expert. If the player's judgment is correct, the play indicating indicia exposed in the movement of the slide will indicate the numeral 1. If his judgment is incorrect, he then moves the excessive slides of the cards possible to play, that is of the same suit as the card lead by West, or failing cards of this suit, of any of the remaining cards of North's hand, to find which card of North's hand bears the play indicating character corresponding to the play indicating character of the lead of West. The card determined by the expert according to this operation is the card that is played.

The cards from East's hand, which of course are concealed with the expert play indicating characters exposed, are played in sequence, that is the card corresponding to the numeral 1 in the slot will be the card played by East in response to the initial lead of West and so throughout the game. The declarer's, or South's, card indicia are of course exposed. He selects from these cards that card which his judgment indicates as the card to be played in response to the plays made by West, North and East. Having

selected a card, he moves the shutter 15 to determine whether this is the card the expert selects and if not, continues to move the shutters until the expert's proper selected card is determined, which is the card which is played. The game is thus played, each trick taken being indicated on the trick indicator.

In the playing characteristic, the essential feature resides in the complete option on the part 10 of the declarer to select the card to be played from his own and his partner's hands, first according to his own judgment as to such play with the subsequent determination of the proper play according to the expert. Thus, the game is 15 completely played as in ordinary bridge whist, the actual play being determined by the expert with optional selection by the player to compare with that of the expert.

An essential characteristic of the improvement 20 is the provision of single elongated slots each exposing the indicia representing a single playing card and the play indicating character determining the sequence of that play in the game played with the hands as printed on the sheet, 25 together with a single short shutter cooperating with the side edges of each slot and readily movable lengthwise the slot and serving in any one position to permit the exposure of only one of the two respective indicia, that of the card or 30 that of the expert play indicating character.

The game board as adapted for the playing of the new game including five suits is illustrated more particularly in Figure 5. Here the construction is substantially identical with the game 35 board as designed for the playing of the conventional game and comprises a playing board 25 preferably of rectangular outline and formed adjacent each edge with a series of spaced parallel uniform slots 26 of which, for reasons which will 40 later appear, there are seventeen such slots for the player indicated as the South player, seventeen such slots for the player indicated as the North player, and sixteen such slots for each of the players indicated as East and West.

45 There are slots indicated at 27 controlled by slides 28 similar in all respects to the slots 12 and slides 19 of the preferred form through which the bidding as determined by the expert may be exposed. The board is further formed with slots 50 29 through which the dealing hand is indicated and the fact as to the vulnerability of either set of partners and the indicators 30 for marking the tricks taken by each side, all as in the preferred form.

55 The board for this type of game, however, includes a slot 31 through which is exposed the extra card of the deck referred to as the "kitty." This slot 31 may be arranged adjacent one of the bid indicating slots. There is also provided 60 a further slot 32 opposite, for example, the bidding slot of the opposing hand through which the discard remains visible. This discard slot is provided with a slide 33 similar to the slides or shutters 15 of the form first described. The card 65 slots 26 have shutters or slides 34 which, as in the preferred form, may be operated as will later appear.

70 It is, of course, understood that the game board described is played in conjunction with a printed sheet on which appears the hands for each player, the "kitty" and the discard, and with respect to the hands, the cards of which register with the slots 26, there is arranged in alignment with the card indications a number indicated at 75 for each card, the numbers being arranged in

the order in which the expert would play the cards of that hand in playing the game including the four hands marked on the sheet.

As stated, in the new game the successful bidder, which for the purpose of illustration is practically in every instance the one playing the South hand, has the privilege of discarding a card, after becoming the declarer, from his hand or from his partner's hand, known as the dummy, and substituting for the discarded card the card 10 exposed through the slot 31 and known as the "kitty." This card, known as the "kitty," is exposed at all times through the slot 31 and every player is supposed to take this card into consideration in his bidding because if his bidding is successful and he becomes the declarer, he has the right to substitute the "kitty" for one of the cards of his hand.

Of course, in the game apparatus the hands are played from a printed sheet and as the cards 20 are not shiftable, provision must be made for first assuming one of the hands as the declarer. As the declarer has the right to substitute the "kitty" for any selected card in his or the dummy hand, both the declarer's hand and the dummy hand must 25 always include an additional slot through which is exposed the "kitty" in order that this card (the "kitty") will be in the proper hand, according to the expert determination, for the playing of the game. The discard is also, following the expert's selection, a card from either the declarer's hand or his partner's, the dummy's, hand, and as the cards are printed on the sheet from which the game is played, this discard is printed on the sheet to be displayed through the slot 32 but 30 until the game is ready to be played, the discard is covered by the slide 33.

The bidding of the game proceeds according to that in connection with the four-suit game previously described. The bidding by the South 40 hand, which for illustration is the declarer, is made by the player according to his own judgment and a knowledge of the cards of his hand including that of the "kitty," and following a determination of the bid according to his own 45 judgment, the expert bid is determined by the movement of the slide 28 for the bid of the expert, as in the previously described game. When the final bid is reached, the declarer then determines as to the discard from his own or from his 50 partner's hand and then moves the discard slide 33 to determine the proper discard according to the expert. The game is then played according to the general rules of contract bridge, the declarer having the option of determining the cards 55 to be played in sequence from his hand and from his partner's or dummy's exposed hand, and then determining by the number of the card to be played which is the proper card according to the expert.

It is, of course, to be remembered that in accordance with the game previously described, the numbers corresponding to the cards in the respective hands are in sequence and determine by that 65 sequence the proper card to be played according to the expert. However, as the declarer's hand as well as his partner's or the dummy hand are exposed, declarer has the option of selecting the proper card to be played according to his own 70 judgment and then by moving the slide 34 corresponding to that card, determine whether his judgment accords with that of the expert and if in error, seek to find a reason as to why his play is incorrect, because the card selected by the ex- 75

pert to be played is always the card presumed to be played.

Of course, in the representation of the cards, the card bearing indicia visible through the slots 5 **26** each have the proper sequence playing numeral or other character **35**, with the slides **34** cooperating with the walls of the slots **26** being of such length that either the number or card indicia but not both may be exposed. The cards of the East 10 and West hands are selected and the numbers exposed and merely for convenience the parts are arranged so that the numbers or other characters appear in sequence. These cards are played as indicated by their numerals without selection on 15 the part of the player.

The game board is associated with a sheet on which the card indicia, numbers and other details to be visible through the slots are marked, each sheet having different card groupings on 20 the front and back and there being, of course, any number of sheets associated with the game apparatus for the playing of various hands. As in the preferred form, the game apparatus may include a base **36** recessed to receive the printed 25 sheet and to which the game board **25** may be hinged to permit it to be raised to replace the sheets. The board and base may form a part of the apparatus though obviously the sheets may be arranged beneath the board **25** proper without 30 the use of the base.

It is to be particularly emphasized, however, that in both forms of the game apparatus, the elemental purpose is one of instruction because, while the game is actually played trick by trick, 35 the player has the option of selecting the cards to be played by him on each trick from his hand and from his partner's or dummy's hand according to his own judgment, and then by moving the slide corresponding to the card which he has 40 selected, learn from the number corresponding to that card whether it is the proper card to be played according to the expert. The player will thus be instructed as to the error of his own judgment and as to the proper play and it is preferred 45 that the sheets bearing the card and other indicia be printed giving reasons for the playing of the particular cards in each instance to thereby utilize the game apparatus primarily as a means for instructing the player in the proper 50 play, the reasons for these proper plays and the ultimate advantage and improvement in his playing of the game.

What is claimed to be new is:

1. A game educational apparatus including a 55 sheet having indicia thereon representing playing cards arranged in the form of hands, with a character adjacent and in line with each playing card indicia to indicate the order of play of that particular card in the game, and a playing board 60 to overlie the sheet and formed with a series of elongated slots, each of said slots being of a width and length to permit the exposure therethrough of a playing card indicium and a play indicating character peculiar to that playing 65 card indicium, and a single shutter cooperating with the edges of the single slot and movable lengthwise the slot to expose either the playing card indicia or the play indicating character, the length of the slot relative to the length of the

shutter being such that the shutter cannot expose in any position both the playing card indicia and the play indicating character.

2. A construction as defined in claim 1, wherein the shutter comprises a plate, a finger operating 5 projection extending above the plate with the plate having depending side portions formed as guides to slidably embrace the longitudinal edges of the slot with which the shutter cooperates.

3. A game educational apparatus including a 10 sheet having indicia thereon representing playing cards in five suits and a game board through which the indicia of equally divided hands of all cards are visible with the game board further provided with an opening through which a single 15 card is visible to be used in playing the game.

4. A game educational apparatus including a sheet on which cards in hands of sixteen cards in five suits are marked, with the additional marking representing the final card of a deck 20 after the cards forming the hands are arranged, with the hands of one set of partners having included the additional card, and a board through which the cards of all hands and the additional 25 card may be exposed.

5. An educational game apparatus including a sheet on which the cards of five suits of thirteen cards each are divided equally into hands of sixteen cards with the final card printed in each one of two partners' hands and additionally 30 printed spaced from all hands, a board to overlie the printed sheet and formed with slots to expose the cards of all hands at will and to continuously expose the additional card.

6. An educational game apparatus including a sheet on which the cards of five suits of thirteen cards each are divided equally into hands of sixteen cards with the final card printed in each one of two partners' hands and additionally 35 printed spaced from all hands, a board to overlie the printed sheet and formed with slots to expose the cards of all hands at will and to continuously expose the additional card, the sheet markings for the cards of each hand bearing characters indicating the sequence playing of the cards of 40 that hand with a character common to each card, and a slide for each slot whereby the card indicia or the playing character may be independently 45 but not simultaneously exposed.

7. A construction as defined in claim 5, wherein 50 the slots for two of the hands include the playing cards of that hand and the additional card and the slots of the remaining hands indicate the playing cards only.

8. A construction as defined in claim 5, wherein 55 the slots for the hands of the declarer and his partner are seventeen in number and the slots for the card indications of their opponents are sixteen in number.

9. A construction as defined in claim 5, wherein 60 the sheet bearing the card indicia is formed with a card representation indicating a discard from either the hand of the declarer or his partner, the board being formed with a slot through which this discard may be visible, and means 65 cooperating with the slot to normally conceal the discard.

NORMAN R. STERNE.
